UNITED STATES PATENT OFFICE.

ISAAC KARPEN, OF CHICAGO, ILLINOIS, ASSIGNOR TO S. KARPEN & BROS.,
OF CHICAGO, ILLINOIS, A CORPORATION OF WEST VIRGINIA.

MATTRESS, CUSHION, &c.

No. 833,464.

Specification of Letters Patent.

Patented Oct. 16, 1906.

Application filed June 25, 1906. Serial No. 323,228.

To all whom it may concern:

Be it known that I, ISAAC KARPEN, a citizen of the United States, residing at Chicago, in the county of Cook and State of Illinois, have invented a new and useful Improvement in Mattresses, Cushions, &c., of which the following is a specification.

My invention relates particularly to the upholstery of mattresses, cushions, couches, sofa-beds, &c.

My primary object is to provide for a more compact arrangement of springs than has heretofore been known and to improve the construction in other respects, economy of construction being also a consideration.

The invention is illustrated in the accompanying drawings, in which—

Figure 1 represents a broken plan view of a cushion or mattress constructed in accordance with my invention; Fig. 2, a broken plan view of a flexible spring-casing in one stage of development of the same; Fig. 3, a broken perspective view of the same in another stage of development; Fig. 4, a broken perspective view of the same in another stage of development; Fig. 5, a sectional view illustrating the grouping of the spring pockets or receptacles during the insertion of the springs, and Fig. 6 a similar section showing the grouping after completion of a row of springs.

The mattress, cushion, or the like is in the preferred construction composed of a series of spring-casings f and square helical springs f' , inclosed in the pockets of each casing. Each casing is of cloth fabric—such as duck, canvas, cheese-cloth, or the like—and is formed with a series of alined pockets or individual receptacles for the several springs of each row. The several casings are arranged in close parallel relation with the springs on end and are joined together by any suitable means, as by stitching.

Each casing f preferably comprises two strips of fabric $f^2 f^3$ of uniform width laid one upon the other, with one lateral border of each strip forming a projection or flap f^4 . The strips are joined by parallel rows of stitches $f^5 f^6 f^7 f^8 f^9$, marking the separation of the pockets. The stitches preferably stop short of the overlapping edges of the strips. In Fig. 3 the folding of the fabrics to produce the outlines of pockets of square cross-section and the folding of the flaps to enable

them to be folded over to form the ends of 55 the pockets is illustrated, and in Fig. 4 one of the flaps is shown folded over and partially sewed in place. By preference one of the flaps is sewed to close the pockets at one end before the springs are inserted, and after the 60 insertion of the springs the other flap is sewed on a special machine to close the pockets at the other end.

In the operation of folding the fabric to form the open-ended box-form envelops or 65 receptacles for the springs the stitching having the oddly-indexed characters mark corners of the envelops at the lower side of the casing, and the stitchings having the evenly-indexed characters mark corners of the envelops at the upper side of the casing, the 70 stitchings being at diagonally opposite lateral corners of the receptacles. In Fig. 2 the points on the flap and receptacles which are brought together when the flap is folded to 75 the sewing position are indicated by the characters $a b c d e$, the points having the same letter being brought together. In Fig. 3 the corners at the near ends of the receptacles not previously marked are indicated by 80 the characters $g g' g^2 g^3 g^4$. The upwardly-drawn folds of the flap f^4 are designated h , and it will be observed that one side or partition-wall of each receptacle is formed by extending this fold across the casing, and the 85 opposite sides or partition-walls of the receptacles are formed by downwardly-drawn folds k . After the folds are completed, as shown in Fig. 4, the edges are joined together 90 by stitching k , a portion of which only is shown.

It will be understood that after the stitching is completed the receptacles will be tied together and maintained in the condition shown in Fig. 6, it being understood that the 95 operation of sewing the remaining flap is similar to that already described, except that the sewing is effected after the insertion of the springs. The final operation is performed on a sewing-machine having a table 100 depressed the thickness of the springs to enable the edges of the fabric to be readily joined. When the casings with the springs inclosed are assembled and joined together, as shown in Fig. 1, a compact arrangement 105 of the springs results and a bed spring or cushion provided having thorough uniformity of resistance throughout its surface. It

will be understood that any suitable pad or cover may be applied to the mattress or cushion.

What I regard as new, and desire to secure by Letters Patent, is—

1. A spring-bottom of the character set forth comprising parallel rows of casings with spring-pockets of angular shape formed therein, and helical springs of angular form inclosed in said pockets.
2. A spring-bottom of the character set forth comprising parallel casings having pockets of rectangular form, and helical springs of rectangular form inclosed in said pockets, each casing comprising overlapping strips of fabric joined by parallel, transverse rows of stitchings and formed into rectangular shape, with the flaps folded and forming ends for the pockets.
3. A spring-bottom comprising parallel connected casings, each casing having a series of pockets of substantially rectangular form, and helical springs of rectangular form

inclosed in said pockets, each casing comprising two strips of fabric of uniform width ²⁵ with overlapping portions joined by parallel transverse rows of stitchings, lateral margins of the strips projecting to form flaps, the strips of material being alternately folded in opposite directions to form rectangular receptacles, and the projecting flaps being folded and connected with the bodies of receptacles thus formed, thereby forming the ends of the receptacles, substantially as and for the purpose set forth. ³⁰

4. A casing having individual spring-receptacles, and springs contained in said receptacles, said casing comprising strips of fabric joined by parallel rows of stitchings and having projecting flaps folded and connected with the bodies of the receptacles, for the purpose set forth. ³⁵ ⁴⁰

ISAAC KARPEN.
